UNITED STATES PATENT OFFICE.

JOHN T. CURRAN, OF BROOKLYN, ASSIGNOR TO TIFFANY & CO., OF NEW YORK, N. Y.

DESIGN FOR A HANDLE FOR FORKS, &c.

SPECIFICATION forming part of Design No. 22,829, dated October 10, 1893.

Application filed August 28, 1893. Serial No. 484,237. Term of patent 7 years.

To all whom it may concern:

Be it known that I, JOHN T. CURRAN, a citizen of the United States, residing at Brooklyn, Kings county, State of New York, have 5 invented and produced a new and original Design for the Handles of Forks, &c., of which the following is a specification, reference being had to the accompanying drawing.

The drawing shows a front view of my design.

The leading feature of my design consists in the waved contour of the side edges of the stem of the handle and a shield-like surface wrought into the upper end thereof, sur- 15 mounted by a crest of curved lines branching from the top of the shield outward and down to the sides thereof.

A is the stem of the handle, and a, b are the waved edges thereof. These edges are orna-

mented by waving lines a', b' wrought in the handle and following the adjoining edges between the outward swells of which are perforated scroll ornaments c.

B is the shield-like surface. It has suitable curved lines d surrounding it, some of which 25 join the waved lines of the stem below.

C is the crest having the curved lines e ending in volutes, extending from the top of the shield C down to both sides. The spaces between these curved lines are partly open. 30

What I claim is—

The design for the handles of forks &c. consisting of the design substantially as shown.

JOHN T. CURRAN.
